UNITED STATES PATENT OFFICE

105,876

DESIGN FOR A BUFFET

Leo Jiranek, New York, N. Y., assignor to Heywood-Wakefield Company, Gardner, Mass., a corporation of Massachusetts

Application July 6, 1937, Serial No. 70,267

Term of patent 3½ years

To all whom it may concern:

Be it known that I, Leo Jiranek, a citizen of the United States and a resident of New York, county of New York, and State of New York, have invented a new, original, and ornamental Design for a Buffet, of which the following is a specification, reference being had to the accompanying drawing, forming a part thereof, in which Fig. 1 is a perspective view of a buffet showing my new design. Fig. 2 is a fragmentary detail horizontal sectional view on an enlarged scale on the line 2—2 of Fig. 1 and Fig. 3 is a fragmentary detail vertical sectional view also on an enlarged scale on the line 3—3 of Fig. 1.

I claim:

The ornamental design for a buffet substantially as shown.

LEO JIRANEK.
